(57) **CLAIM**

The ornamental design for a portion of an infusion solution bag, as shown and described.

DESCRIPTION

FIG. 1 is a perspective view of the design according to the invention;

FIG. 2 is a left side view thereof;

FIG. 3 is a top view thereof;

FIG. 4 is a bottom view thereof;

FIG. 5 is a front view thereof;

FIG. 6 is a right side view thereof;

FIG. 7 is a rear view thereof;

FIG. 8 is a cross section view, shown at a larger scale, taken along line 8—8 as shown in FIG. 5.

FIG. 9 is a cross section view, shown at a larger scale, taken along line 9—9 as shown in FIG. 5.

FIG. 10 is a cross section view, shown at a larger scale, taken along line 10—10 as shown in FIG. 5; and,

FIG. 11 is a cross section view, shown at a larger scale, taken along line 11—11 as shown in FIG. 5.

The broken lines are for illustrative purposes only and form no part of the claimed design.
